ELECTRICAL TERMINAL BLOCK

Michael S. Weinstock, 15050 Burbank Blvd.,
Van Nuys, Calif.

Filed Aug. 24, 1964, Ser. No. 81,420

Term of patent 14 years

(Cl. D26—1)

FIG. 1

FIG. 2

FIG. 3

FIG. 4

FIG. 5

FIGURE 1 is a top plan view of an electrical terminal block showing my new design;

FIGURE 2 is a front elevational view thereof;

FIGURE 3 is a right-end elevational view thereof;

FIGURE 4 is a cross-sectional view thereof taken on line 4—4 of FIGURE 2; and

FIGURE 5 is a cross-sectional view thereof taken on line 5—5 of FIGURE 2.

I claim:

The ornamental design for an electrical terminal block, as shown.
